United States Patent Office

Des. 218,713
Patented Sept. 15, 1970

218,713

COMBINED PHONOGRAPH AND SLIDE PROJECTOR

Terry L. Bernard, Cincinnati, Ohio, assignor to Kenner
Products Company, Cincinnati, Ohio, a corporation of
Delaware

Filed Aug. 22, 1969, Ser. No. 18,819

Term of patent 14 years

Int. Cl. D16—03

U.S. Cl. D61—1

Fig. 1

Fig. 2

FIG. 1 is a front-side perspective view of the combined phonograph and slide projector taken from a front corner thereof showing my new design;

FIG. 2 is a rear-side perspective view thereof taken from a rear corner opposite to said front corner shown in FIG. 1;

FIG. 3 is a front perspective view thereof;

FIG. 4 is a rear-top perspective view thereof; and

FIG. 5 is a bottom view thereof.

I claim:

The ornamental design for a combined phonograph and slide projector, substantially as shown.
